UNITED STATES PATENT OFFICE.

SELDEN H. HALL, OF POUGHKEEPSIE, NEW YORK, ASSIGNOR TO THE DE LAVAL SEPARATOR COMPANY, OF NEW YORK, N. Y., A CORPORATION OF NEW JERSEY.

VACUUM-PUMP.

1,374,650.

Specification of Letters Patent. Patented Apr. 12, 1921.

Application filed February 3, 1920. Serial No. 355,999.

To all whom it may concern:

Be it known that I, SELDEN H. HALL, a citizen of the United States, residing at Poughkeepsie, county of Dutchess, and State 5 of New York, have invented a new and useful Improvement in Vacuum-Pumps, of which the following is a full, clear, and exact description, reference being had to the accompanying drawings, which form a part of 10 this specification.

My invention relates to pumps of the known type having an approximately cylindrical body in which there is eccentrically mounted a rotor carrying vanes adapted to 15 slide outward and press against the inside of the body. The body, in well designed pumps of this type, varies from the cylindrical form enough to cause all chords drawn through the center of rotation of the rotor 20 to be equal.

In order that this type of pump may run easily, appreciable clearances must be left between the rotor and the body, between the 25 ends of the vanes and the heads, and in the rotor at the sides of the vanes. Frequently a considerable quantity of oil is used to seal these clearances.

Many of these pumps are used in the operation of cow milking machines. In such 30 cases the inlet to the pump is always at about half of atmospheric pressure (about 15-16 inches of vacuum) and the discharge is at atmospheric pressure.

Pumps of the general construction above 35 specified exhibit three notable faults. First, the discharge is very noisy; second, the discharged air carries with it a large quantity of oil in such a finely divided state that it is impossible to catch it in an oil separator; 40 and third, the efficiency is low.

I have found that all three faults in operation are due to one error in construction, namely: that the ports between the compressing chamber and the discharge passage 45 are allowed to open before the pressure in the compressing chamber is equal to that in the discharge passage. The result is that at every opening of the port there is a rush of air from the discharge passage into the compressing chamber and then, as the vane moves forward, this air, in addition to that drawn in at the suction inlet, has to be forced out through the discharge ports. 50 With a four vane pump running five hundred revolutions per minute there are two 55

thousand of these inward and outward rushes of air per minute, causing a very disagreeable pulsating noise. When the pump is oil-sealed, as it must be to prevent excessive leakage and insure sufficient lubrication, 60 there is always some oil being carried out with the discharged air. The above mentioned pulsations tear this oil up and atomize it so thoroughly that it passes through any oil separator that may be provided and 65 escapes in the form of a fog in the discharge, thus wasting oil and making a dirty deposit over everything in the vicinity. As all air that enters the compressing chamber through these discharge ports must be forced out 70 again through the same ports, pneumatic resistance to movement of the vanes is increased, in some cases, by as much as twenty per cent.

The object of my invention is to make a 75 pump which shall be quiet in operation, will not waste oil and will have a maximum capacity and maximum efficiency.

I obtain maximum capacity by making the inlet ports of ample size and of such length 80 that each vane crosses the port ends at the instant that the volume between it and the vane ahead is at a maximum. I obtain quiet operation, conservation of oil and high efficiency by making the discharge ports of 85 ample size and of such length that each vane crosses the port ends at the instant that the pressure in the space behind it is about equal to the pressure in the discharge passage.

In the accompanying drawings, which 90 show a pump embodying this invention in a preferred form:

Figure 1 is a section through the pump parallel to the shaft.

Fig. 2 is a section on line 2-2 of Fig. 1 95 at right angles to the shaft.

Fig. 3 is a section on line 3-3 of Fig. 1, showing the shape of the oil reservoir at the pulley end.

The rotor *a* is mounted on a shaft *b* carried by bearings in the heads *c* and *d*. The rotor has four slots in which vanes or wings *e* slide toward and from the shaft. Spacers *f* maintain a uniform distance between opposite vanes. In the outer edges of the 100 vanes *e* are grooves in which semi-circular rods *g* oscillate.

Between the heads *c* and *d* is a housing *h* having a bore of such shape that all diameters (or chords) measured through the cen- 110

ter of the shaft *b* are equal. At one side of the housing is an inlet chamber *i* connected with the bore by the ports *j* and at the other side is an outlet chamber *k* connected with the bore by the port *l*.

The bottom end of the lower port *j* is so located that at the instant the tip *g* on the end of a vane *e* passes over and closes it, the space between that vane and the vane 10 ahead of it is at a maximum.

The lower end of port *l* is so located that the tip *g* of a vane *e* will pass over it and open the port at the time that the pressures on the two sides of such vane are equal, and 15 at the time that the volume between that vane and the next following vane bears the same ratio to the maximum volume that the inlet pressure divided by its absolute temperature bears to the discharge pressure divided by the discharge temperature.

From the outlet chamber *k* a passage *m* leads to the central chamber of the oil separator, the upper half of which is separated from the side chambers by the half partitions *n* and *o*. From the side chambers, passages *p* lead to the exhaust pipe. Across the bottom of the central chamber is a dividing fence *q*. From the side chamber of the oil separator there lead to the shaft oil 30 holes *r* and *s* having branches *t* and *u* communicating with the inside of the rotor *a*.

Formed within the heads *c* and *d* are oil reservoirs *v* and *w* communicating with the inside of the rotor *a* by holes *x* and *y* having their lower edges above the bottom of the inside of the rotor. One head *d* carries a hollow axle 10 around which the pulley 11 revolves on bearing rollers 12 and drives the shaft *b* through the flexible coupling 13.

40. In order to have an easy running pump the rotor *a* is made slightly shorter than the housing *h*, giving clearance between it and the heads, and it is so located that there is an appreciable clearance between the top 45 of the rotor and the top of the housing. The vanes *e* are made easy fits in their slots and the separators *f* are made so short that the vanes turn freely in the housing. These clearances, while desirable for easy running, all tend to cause leakage.

When in operation, the pump should contain sufficient oil to cause the level in the reservoirs *v* and *w* to reach about one-quarter inch to three-eighth inch above the bottom of the holes *x* and *y*. This oil will flow through the holes until it fills the annular space from the bottom of the holes outward to the shell of the rotor. Centrifugal force, due to the rapid rotation of this oil, will 55 prevent the entrance of excess oil. Centrifugal force will also force the oil into all the clearance spaces and so seal them. Oil that passes outward between the rotor and the heads and through the clearances at the 60 sides of the vanes will seal the ends and

outer edges of the wings. Any excess oil reaching the spaces between the rotor and the housing will be thrown, with the discharging air, outward through the port *l* into the chamber *k* and then upward at 70 high velocity through the passage *m*. Because of the circular path that the air is compelled to take in the oil separator, all oil in appreciable sized drops will be thrown against the wall and will collect in 75 the bottom, while the air will pass under the partitions *n* and *o*, upward through the passages *p* and out through the exhaust pipe. If the oil were so finely divided as to form a fog, some of it would be carried 80 around and out with the air; but by arranging the discharge port as hereinbefore described, with consequent avoidance of pulsations at the discharge, the atomization of oil is prevented and its waste avoided.

85. As the oil flows down the back wall of the separator, it will be divided, by the fence *q*, into two streams, one flowing to each end of the separator and thence downward through the holes *r* and *s* to lubricate 90 the bearings. All oil in excess of that required for the bearings will flow through the holes *t* and *u* to the interior of the rotor, ready to repeat the cycle.

95. Oil that works outward through the bearing in the head *c* falls into the reservoir *v*. Oil that works outward through the bearing in the head *d* enters the hub of the pulley 11 and oils the roller bearing. When the hub is filled with oil, any additional 100 supply forces some out through the hole 22 in the inner flange of the hub and it escapes into the reservoir *w*.

When the pump stops, all the oil from the annulus inside the rotor, with all oil from 105 the separator, falls to the bottom of the rotor and a large part of it flows outward through the holes *x* and *y*, to be stored in the reservoirs *v* and *w* until needed again.

If the pump stands idle for a long time, 110 much of the oil from the reservoirs *v* and *w* may leak past the rotor into the bottom of the housing. When the pump is started, the first turn will throw this oil up into the separator, whence it will flow, partly by the 115 holes *r* and *t* and partly by the holes *s* and *u*, to the inside of the rotor, ready to perform its sealing and lubricating function.

With the described porting, the pump has a maximum capacity for its size, the discharge is relatively quiet, and the oil sent out of the pump with the discharge will be in such large drops that practically all of it will be caught in the oil separator and returned to the pump.

120. Certain novel features of the construction herein shown, particularly the arrangement of oil reservoirs below the bearing and open to the atmosphere and adapted to catch drips from the bearings and the pulley hub, 125

to supply oil to form a sealing annulus within the rotor and to receive oil without over-flow when the pump stops, are not herein claimed, as they are not my invention, but 5 form the subject-matter of another application filed by Meredith Leitch filed February 3, 1920, Serial No. 356014.

Having now fully described my invention, what I claim and desire to protect by Letters Patent is:

- 10 1. In a vacuum pump of the sliding vane type designed for producing a specific degree of exhaustion, the combination with a rotor and sliding vanes, of a body having a discharge port extending through such arc 15 of the body as to be opened by a vane passing over it at substantially the time that the pressures on the two sides of the vane are equal.
- 20 2. In a vacuum pump of the sliding vane type, the combination with a body having an inlet and a discharge, a contained rotor and sliding vanes on the rotor, said rotor and vanes having appreciable clearances, of 25 means to seal said clearances with a body of oil, and means to minimize atomization of oil in the discharge, said means comprising the positioning of the port communicating with the discharge so that it will be 30 covered by a vane at the time that the pres-

sures on the two sides of the vane are substantially equal.

3. In a vacuum pump of the sliding vane type, the combination with a body having an inlet and a discharge, a contained rotor 35 and sliding vanes on the rotor, said rotor and vanes having appreciable clearances, of means to seal said clearances with a body of oil, and means to prevent pulsation of air at said discharge.

4. In a vacuum pump of the sliding vane type, the combination with a rotor and sliding vanes, of a body inclosing the rotor and arranged in eccentric relation thereto so that the volume between the rotor, the body and 45 adjacent vanes varies in the rotation of the rotor and vanes, said body having an inlet port extending through such arc of the body as to be closed by a vane passing over it at substantially the same time that the volume 50 between such vane and the vane in advance thereof is at a maximum, said body having an outlet port so positioned as to be opened by a vane passing over it at the time that the pressures on the two sides of the vane 55 are substantially equal.

In testimony of which invention, I have hereunto set my hand, at Poughkeepsie, N. Y., on this 29 day of January, 1920.

SELDEN H. HALL.
